[57] CLAIM

The ornamental design for a fence caddy, and shown as described.

DESCRIPTION

FIG. 1 is a top, front, and right side perspective view of a fence caddy showing my new design;
FIG. 2 is a front elevational view thereof;
FIG. 3 is a right side elevational view thereof, the left side being a mirror image of that shown;
FIG. 4 is a rear elevational view thereof;
FIG. 5 is a top plan view thereof;
FIG. 6 is a bottom plan view thereof; and,
FIG. 7 is a top, front, and right side perspective view of an alternate embodiment of a fence caddy showing my new design.
The broken-line disclosure of a portion of a chain-link fence in the views is for illustrative purposes only and forms no part of the claimed design.
